CLAIM

The ornamental design for a mirror frame, as shown and described.

DESCRIPTION

FIG. 1 is a top, front and right side perspective view of a mirror frame showing my new design;

FIG. 2 is a top plan view thereof (the bottom plan is a mirror image);

FIG. 3 is a front elevational view;

FIG. 4 is a left side elevational view (the right side view is a mirror image thereof);

FIG. 5 is a rear elevational view; and,

FIG. 6 is a partial cross sectional view taken along the lines 6—6 of FIG. 5.

FIG. 1

FIG. 2

FIG. 3

FIG. 4

FIG. 6

FIG. 5
